— FIG. 5. —

Dec. 1018

Garrettson Smith & Henry Brown, of Philadelphia Pa.

Assignors to

Leibrandt McDowell & Co. of same place.

Letters Patent No. 1018 Dated June 29, 1858.

The schedule referred to in these Letters Patent and making part of the same.

To all whom it may concern:

Be it known that we, Garrettson Smith and Henry Brown, of the City of Philadelphia and State of Pennsylvania, have invented or produced a new and original design for the plates of a Cooking Stove, termed the "Lehigh", and we do hereby declare the following to be a full and exact description of the same, reference being had to the

accompanying drawing, which forms a part of this specification, and in which

Fig. 1. represents one of the side plates of the stove.

Fig. 2, the front plate.

Fig. 3, the back plate.

Fig. 4, an outline of the stove in perspective.

Fig. 5, a section, full size, of the moulding on the edge of the top plate.

Fig. 6, a section of the moulding on the edge of the bottom plate.

The side plate (Fig. 1.) is edged with a plain moulding a and is furnished with the oven door A, fire door B, and oven door C, all of which have foliated ornaments of corresponding character in alto-relievo, and all are edged with plain mouldings, in addition to which the curved corner of the oven door is ornamented with foliage b.

On the side plate above the oven door is a foliated scroll D, and on the latter the name of the stove in raised letters.

The front plate (Fig. 2.) is also edged with plain mouldings and has the usual air openings E and doors F. In front of the grate, the mouldings are foliated ornaments of these being similar in character to those of the side plate.

The end plate (Fig. 3.) has also plain mouldings on the side and bottom, and is rounded in the middle, the rounded portion having the foliated ornament d.

The top plate F is plain, with the exception of a moulding, represented in section (Fig. 5.) on the edge.

The bottom plate G, is also plain, with the exception of the moulding (Fig. 6.) on its edge.

We claim. The combination of the ornamental figures and forms represented in and by the accompanying drawing, forming together an ornamental design for the plates of a cooking stove, termed the "Lehigh".

Excl

In testimony whereof, we have signed our names to this specification before two subscribing witnesses.

Witnessed.
O. Brazer
Henry Odiorne.
